UNITED STATES PATENT OFFICE.

POPKO REINDER DIJKSTERHUIS, OF EINDHOVEN, NETHERLANDS, ASSIGNOR TO
N. V. PHILIPS' GLOEILAMPENFABRIEKEN, OF EINDHOVEN, NETHERLANDS.

ELECTRIC APPARATUS.

Application filed February 18, 1925, Serial No. 10,146, and in Netherlands April 5, 1924.

- This invention relates to electric apparatus comprising an incandescent cathode of highly refractory metal such for example as tungsten, more particularly to the attachment 5 of a filament for a high current intensity to a leading-in wire in an electric apparatus which may be, for example, an electric incandescent lamp or an electric discharge tube.
- 10 It is known to connect a filament to its leading-in wire by welding. In the case of such a connection and especially if the filament is destined for a high current intensity, there easily occurs breakage of the filament near the weld, which is probably due, at least partly, to the filament becoming brittle near the weld.
- 15 It has also been proposed already to attach a filament of highly refractory metal to a leading-in wire by bending the end of the latter and by clamping the filament in the loop thus formed. This construction is, however, not suitable for current wires for high current intensities.
- 20 According to the invention, one or each of the two ends of a filament is clamped in an aperture, split or groove provided in the end of a leading-in wire.
- According to the invention, the end of the 25 filament may be so bent as to form a loop which then is inserted into a groove in the leading-in wire, a pin which passes right across said groove being put through the eye of the loop. Moreover a wire is preferably wound round the free end of the loop protruding from the groove together with the end of the filament.
- According to the invention, the number 30 of layers of wire windings may be so chosen as to increase towards the leading-in wire.
- The accompanying drawing illustrates, by way of example, a construction showing the attachment of the filament in accordance with the invention. In the drawing:
- 45 Figure 1 is a view of a leading-in wire with a filament fixed to it.
- Figure 2 is a section of the leading-in wire shewn in Figure 1 with the filament attached to it.
- 50 Figure 3 represents a tubular incandescent lamp provided with a filament attached according to the invention.
- According to the Figures 1 and 2 of the drawing the end of a filament 1 is so bent as 55 to form a loop 2, which is inserted into a
- groove 3 provided in the end of a leading-in wire 4. A rivet 5 passes through the eye of the loop 2, the free end 7 of which protrudes from the groove 3 and is secured on to the filament by means of a helically wound wire 6. The filament 1 may consist, for example, of tungsten, the leading-in wire 4 as well as the rivet 5 may be made of molybdenum. The wire 6 consists, for example, of molybdenum or tungsten. 60
- As the free end 7 is located against the filament 1, the diameter of the wire near the weld is increased, owing to which already the temperature of the wire in this place is decreased. The helical wire 6 carrying itself 65 also part of the current, still further increases this diameter so that the temperature decreases still more.
- Figure 3 represents an incandescent lamp consisting of a glass vessel 10 into the 70 wall of which leading-in wires 11 and 12 are hermetically sealed. The filament 13 is attached to these leading-in wires in the manner shewn in the Figures 1 and 2. The vessel 10 may be highly evacuated in any known 75 manner.
- The invention may be applied with particular advantages to filaments for high current intensities, for example, of more than 80 30 amperes. This attachment of the filament may not only be utilized in incandescent lamps for a high candle power, but it may also be used advantageously, for example, in transmission tubes for wireless telegraphy or other discharge tubes for high 85 capacities.
- What I claim is:
- An electric apparatus, comprising a filament of highly refractory metal, one or both 90 of the two ends of which is bent back upon itself so as to form a loop which is inserted into a groove of the leading-in wire and is clamped in said groove by a rivet passing through the eye of the loop, the free end 95 of which, protruding from the groove, is secured on to the filament by a wire wound around the said two parts of the filament in such a way that the number of layers of the wire windings gradually increases towards the leading-in wire. 100
- In testimony whereof I have hereunto set my hand, at the city of Eindhoven, this 29th day of January, A. D. 1925. 105
